[57] CLAIM

The ornamental design for a screwdriver handle, as shown and described.

DESCRIPTION

FIG. 1 is a front elevational view of a screwdriver handle showing my new design;

FIG. 2 is a top plan view thereof;

FIG. 3 is a bottom plan view thereof;

FIG. 4 is a left side elevational view thereof;

FIG. 5 is a right side elevational view thereof; and,

FIG. 6 is a cross sectional view thereof, taken along the line 6—6 of FIG. 1.

The broken line showing of a removable socket on FIG. 1 is for illustrative purposes only and forms no part of the claimed design.

FIG. 2

FIG. 1

FIG. 4

FIG. 5

FIG. 6

FIG. 3
